UNITED STATES PATENT OFFICE

CLARENCE G. EDWARDS, OF LOS ANGELES, CALIFORNIA

COUNTERTHRUST-PRESSURE MOTOR

Application filed July 15, 1929. Serial No. 378,514.

My invention is a counter-thrust pressure motor and has to do with improvements in a type of motor set forth in my Patent No. 1,678,424, issued July 24, 1928, for counter thrust pressure motor, U. S. Patent No. 5 1,701,322, issued February 5, 1929, for counter thrust pressure motor and my application for U. S. Letters Patent filed April 11, 1928, Serial No. 269,087, for counter thrust pressure motor.

An object of my present invention is to simplify the construction of the piston cylinder and hanger of a counter thrust motor and in which the cylinder is especially 15 adapted for air cooling.

Another object of my invention is to use a construction of hanger on the piston which will materially lighten the weight carried by the piston and effectively operate to exert a 20 counter thrust in the operation of the piston in the cylinder.

Another object of my invention is forming a cylinder with a curved groove in which the hanger on the piston fits. This hanger is 25 preferably made in the form of a strap fitting on the side of the piston and having angular ends of flanges engaging the top and the bottom of the piston, an inverted cup-shaped structure on the hanger fits in the groove and 30 receives the pressure of the gases forced down into the groove in the operation of the engine.

Another object of my invention is utilizing the detachable cap over the slot in the cylinder. This cap and the cylinder are air cooled 35 by fins or the like. The removable cap allows for any access to the side of the cylinder.

My invention is illustrated in the accompanying drawings, in which,

40 Figure 1 is a vertical section through an engine of my invention;

Fig. 2 is a partial transverse section on the line 2—2 of Fig. 1;

Fig. 3 is a perspective view of the hanger 45 to fit on the piston.

Fig. 4 is a view similar to Fig. 2 with the cap forming the slot removed;

Fig. 5 is an enlarged partial section of Fig. 2, showing the manner of securing the cap to the cylinder;

Fig. 6 is an elevation of the cap.

In the drawings, the engine base is designated 11 having a crank case 12 and a cylinder 13 mounted on the base, this cylinder being provided with a cylinder head 14. The cylinder has a longitudinal groove 15, this groove being formed with two parallel sides 16 joined by a semi cylinder 17.

The piston 18 has a slight recess 19 at the top and another recess 20 at the bottom extending partly inwardly from the outer periphery. The hanger assembly 21 has a vertical strap 22 fixed against the side of the piston as shown in Figs. 1 and 2 and has a top in-turned flange 23, and a lower in-turned flange 24, these flanges fitting in the recesses 19 and 20 respectively. The strap is secured to the side wall of the piston by screws 25 having counter sunk heads. The piston rings 26 fit in the grooves behind the strap 22.

At the lower end of the strap there is an inverted cup 27. This is formed with a flat top 28 and with parallel vertical sides 29 joined by a semi-cylindrical portion 30 so that this cup fits in the groove 15 having a close sliding fit therein. The marginal edges of the strap 22 are provided with vertical ribs 31 which aid in confining the gas pressure at the joint of the cylinder and cap.

The groove in the general construction is formed by having a vertical slot 32 in the cylinder, the strap 22 attached to the piston fitting in this slot. A removable cap 33 has flanges 34 on opposite sides and these flanges are provided with transverse slots 35 to allow bolting of the cap on the cylinder. The special manner of bolting is indicated particularly in Figs. 2 and 5 which illustrates the cylinders as having countersunk holes 36 adjacent the slot 32. Bolts 37

37 extend through these holes and each has a nut 38 threaded thereon. By this means the bolts are fastened tight to the cylinders, the heads 39 of the bolts being outside of the 5 wearing surface 40 of the cylinders. The bolts have a threaded socket 41 in which is threaded the screws 42 which screws engage a cover 43. The bolts are arranged to extend outwardly through the lateral slots 35 in the cap 33 and the cover 43 engages the flanges of the cap so that when the screws 42 are tightened the cap is bolted solidly to the cylinder.

There is preferably a packing gasket 44 used between the outside of the cylinder and the cap 33 to form a gas tight joint. The cylinder is cooled by having cooling vanes 45 thereon and the cap also has cooling vanes 46. If desired the piston may be counterbalanced by having an enlargement 47 cast therein which may be ground or filed off to balance the hanger.

With this construction as above described, it will be seen that a comparatively light 25 structure forms the hanger and the inverted cup 27 at the bottom of the piston on one side, the detachable cap covering the vertical slot in the cylinders allows inspection of the hanger by removing the cap and the clearance 30 of the inverted cup in the channel 15 is adjustable by the packing gaskets 44. The bolts holding the cap in place are rigidly secured to the cylinder so that it is not necessary to remove the bolts when removing the cap and 35 as the heads of these bolts are countersunk, they do not interfere with the operation of the piston.

In operation the exploded and burning gases fill the channel 15 and give a lateral 40 pressure on the piston, thus counter-balancing the lateral pressure due to the reaction of the gases on the piston head and the connecting rod against the crank when in an inclined position.

45 Various changes may be made in the principles of my invention without departing from the spirit thereof as set forth in the description, drawings and claims.

I claim:

50 1. A motor having a cylinder with a vertical slot, a cap forming a channel on the cylinder at the said slot, a piston having a hanger operating in the said slot and channel, the hanger overlapping the joint between the cylinder and the cap.

55 2. A motor having a cylinder with a longitudinal slot, a cap secured to the cylinder and forming a channel at the said slot, a piston having a hanger slidably in the slot with a projection forming a closure for the channel, the marginal edges of the hanger overlapping the joint between the cap and the cylinder.

60 3. A motor having a cylinder with a longitudinal slot, a cap secured to the cylinder and forming a channel on the outside of the slot,

a hanger secured to the sides of the piston and having a hollow projection, the hollow projection forming a closure for the channel and the main body of the hanger operating in the said slot, the marginal edges of the 70 hanger overlapping the joint between the cap and the cylinder.

4. A motor having a cylinder with a longitudinal slot, a cap having an arched curve fitting over the slot and forming a channel, 75 means secured to the cylinder from the inside thereof to clamp the cap to the side of the cylinder, a piston having a hanger operating in said slot with a projection forming a closure for the channel, the marginal edges 80 of the hanger overlapping the joint between the cylinder and the cap.

5. A motor having a cylinder with a longitudinal slot, bolts fitting on the inside of the cylinder adjacent opposite edges of the slot, 85 a cap fitted over the slot and secured to the said bolts, the cap forming a channel, and a piston having a hanger operating in the said slot with a projection forming a closure for the channel.

6. A motor having a cylinder with a longitudinal slot and bolts secured to the cylinder on the inside thereof adjacent the marginal edges of the slot, a cap having a screw threaded means attaching same to the 95 bolts, the cap forming a channel, and a piston having a hanger, the hanger operating in the slot and with a projection forming a closure for the channel.

7. In a motor, a cylinder having a longitudinal slot with bolts secured to the cylinder from the inside adjacent the marginal edges of the slot, the heads of the bolts being counter-sunk, means attaching said bolts to the cylinder, each bolt having a socket, a cover cap fitting over the slot and screw threaded means securing the cap to the 100 sockets of the bolts.

8. In a motor as claimed in claim 7, the cap having marginal flanges with transverse slots, the said bolts fitting in the said slots, and covers fitting over the flanges and secured to the bolts by screws threaded in the 105 sockets.

9. In a motor, a cylinder having a longitudinal slot, a cap forming a closure therefor and having marginal flanges in transverse slots, a series of bolts fitting through holes in the cylinder on opposite sides of the slot, the heads of the bolts being counter-sunk, nuts on the bolts on the outside of the cylinder, each bolt having a socket, a cover bearing on the flange of the cap and at each bolt, and a screw extending through the cover into 110 the socket of each bolt.

10. In a motor, a cylinder having a longitudinal channel, a piston having a hanger in the form of a strap, the ends of the strap extending transversely over the top and bot-

tom of the piston, and said hanger having a projection operating in the said channel.

11. In a motor, a cylinder having a longitudinal channel, a piston having a hanger in the form of a strap secured to the side of the piston and having end flanges engaging over the top and bottom of the piston, and a hollow projection on the hanger operating in the said channel.

10 12. In a motor as claimed in claim 11, the hanger having longitudinal ribs on its marginal edge, such ribs being adapted to cover a joint between the cylinder proper and a structure forming the channel.

15 In testimony whereof I have signed my name to this specification.

CLARENCE G. EDWARDS.
